UNITED STATES PATENT OFFICE.

DANIEL C. HYDE, OF NEW YORK, N. Y.

DESIGN FOR A STAIR AND ROOM CORNER-GUARD.

SPECIFICATION forming part of Design No. 13,797, dated March 20, 1883.

Application filed December 20, 1882. Term of patent 7 years.

To all whom it may concern:

Be it known that I, DANIEL C. HYDE, of the city, county, and State of New York, have invented a new and Improved Design for Stair and Room Corner-Guards, of which the following is a full, clear, and exact description.

Reference is to be had to the accompanying drawings, forming a part of this specification, in which similar letters of reference indicate corresponding parts in both figures.

Figure 1 is a front elevation of my newly-designed stair and room corner-guard shown in position for use. Fig. 2 is a front elevation of the same enlarged.

15 The leading features of my design consist in the bead formed in the corner-guard near its edge, and in the flat circular space formed in the center of the concaved surface of the guard.

20 A is the corner-guard, which is made triangular in its general contour and has its edges concaved. In the guard A, near its edge, is formed a bead, B, which may have its convex

or its concave side outward without materially changing its ornamental effect. The surface of the guard is concaved, and in its center is 25 a circular space, C, which is made flat to relieve the surface of the guard, and thus add to the ornamental effect of the design.

Having thus described my invention, I claim as new and desire to secure by Letters Patent— 30

1. The design for a corner-guard herein shown and described, the same consisting of the bead B, formed around the guard A near its edge.

2. The design for a corner-guard herein shown and described, the same consisting of the bead B, formed around the guard A near its edge, and the flat circular space C, formed in the center of the concaved surface of the guard. 35

DANIEL C. HYDE.
